IRONING TABLE

George W. Lewis, Hudson, Mass.

Application October 9, 1936; Serial No. 104,866

5 Claims. (Cl. 38—118)

This invention relates to an improved ironing table of the folding type.

Among the objects of the invention is to secure greater rigidity in the supporting structure and 5 semi-automatic folding of the table.

Other and further objects which reside in details of the construction will be made apparent in the following specification and claims.

In the accompanying drawings which illustrate one embodiment of the invention:

Fig. 1 is a side view of the table in unfolded or operative position;

Fig. 2 is a side view of the table in partially folded position, somewhat short of the position 15 that it automatically assumes when the catch is released;

Fig. 3 is a similar view showing the folding operation carried a step further;

Fig. 4 is a view of the underside of the table 20 with the parts in completely folded position;

Figs. 5, 6 and 7 are detail views of parts of the supporting structure;

Figs. 8, 9, and 10 are views similar to Figs. 1, 2 and 4 respectively but showing an alternative 25 form; and

Fig. 11 is a section substantially on line 11—11 of Fig. 8.

Referring to the drawings, 10 designates an ironing board of usual or desired shape. A pair 30 of spaced cross pieces 11 and 12 are secured to the underside of the board and serve to space two longitudinally positioned members 13 and 14 from the underside of the table. The members 11, 12, 13 and 14 are secured to the board 35 by countersunk bolts or rivets 15 passing through said members at their point of intersection. Cross pieces 11 and 12 may be further secured by screws 16, see Fig. 4.

A pair of legs 17 and 18 are respectively pivoted 40 to members 13 and 14 as at 19 and 20, the pivots 19 and 20 being transversely aligned. The legs 17 and 18 are cross-braced at 21 and the cross braces are held to the legs by diagonal brace rods 23, the ends of which are bent and extend through 45 the legs and cross braces and are upset as indicated at 24 to rivet the cross braces in place. The upper cross brace is slotted at 22 as best shown in Fig. 4 for a purpose later described.

A third supporting "leg" is provided in the 50 form of collapsible frame structure which comprises a strut 25 and two leg members 26 and 27. The upper end of strut 25 is pivoted at 28 to a block 29 secured by rivets 30 to the underside of the board 10. The upper ends of leg members 55 26 and 27 are riveted or otherwise secured as at

31 (Fig. 4) to a rod 32, the ends of which slide in the guideways 33 formed by the spaces between members 13 and 14 and the underside of the table as best shown in Figs. 1 and 2. The lower ends of leg members 26 and 27 are converged together and pivotally connected to opposite sides of the lower end of strut 25 as at 34.

A locking strut member is provided which is shown as comprising two members 35 and 36 respectively pivoted as at 37 to leg members 26 and 27, and connected together at their ends remote from pivots 37 by a rod 38 which serves as a convenient handle for operating the locking strut as later described. The opposite ends of members 35 and 36 are extended slightly beyond 15 pivots 37 as indicated at 39 in Figs. 1 and 2 for a purpose later explained.

Members 35 and 36 are provided with lugs 40 which when the table is in set up position engage the cross brace 21, the latter being beveled as at 20 41 (Figs. 2 and 6) to afford a firm engagement.

The underside of strut 25 is provided along its lower portion with a guide rod 42, the ends of which are bent and secured in the strut to space the intermediate portion of the rod from the strut to form a guideway 43. A V-shaped link 44 has its apex engaged around rod 42 to slide in guideway 43, the ends of the legs of link 44 being pivotally secured to legs 17 and 18, as best shown in Figs. 4 and 7 at 45 by passing the ends through 30 opening in the legs and upsetting the ends. Any suitable collapsible linkage may be substituted for the sliding linkage shown.

The operation will now be described. Referring to Fig. 1 which shows the table in set up position, 35 it will be seen that legs 17—18 and strut 25 are arranged in crossed relation and held against further spreading by V-link 44 which engages the upper end of guideway 43. Rod 32 is held at the right end of guideway 33 by strut 35—36, the 40 lugs 40 of which engage upper brace 21. Members 26—27, 35—36 and 25 thus constitute a rigid triangular member and downward pressure on the right hand portion of the board is for the most part carried down leg members 26—27, the remainder being transmitted by strut 35—36 to legs 17—18 and strut 25. In set up position strut 25 engages in the slot 22 formed in upper brace 21, preventing side sway.

To fold the table strut 35—36 is raised to release 50 lugs 40 from brace 21 whereupon the weight of the table causes leg members 26—27 to collapse about pivot 34 toward strut 25, rod 32 sliding along guideway 33, so that the parts assume substantially the partially folded position shown 55

in Fig. 2 without other effort on the part of the operator than the lifting of strut 35-36 to release lugs 40. As will be seen from Fig. 2, table 10 in its downward movement engages the extended 5 ends 39 of struts 35-36, thereby raising the opposite ends of the struts. In Fig. 2 the parts have been stopped somewhat short of the limit of the "automatic" collapse in order to better illustrate the movement of the parts. The completion 10 of the folding is accomplished by simply swinging the upper end of the board in the direction of the arrow A in Fig. 3 whereupon link 44 drops downwardly in guideway 43 as shown by arrow C while legs 17-18 are drawn towards a collapsed 15 position against the underside of the board as indicated by arrow D. The folding is completed, when the legs 17-18 have approached as near the board as may be conveniently accomplished by movement of the board in direction A, by moving the structure bodily to the left as viewed in Fig. 3 with the weight on legs 17 and 18 as shown in Fig. 4.

In unfolding or setting up the table from collapsed position it is only necessary to tilt the 25 board from the position shown in Fig. 4 towards the position of Fig. 3 when continued pressure on the upper end of the board carries the parts through the positions shown in Figs. 3 and 2 to that of Fig. 1, the lock strut 35-36 dropping into place to releasably lock the parts 30 in position.

In Figs. 8 to 11 inclusive is shown an alternative embodiment of the invention which in some respects is preferable to that previously described in that greater regidity is secured in the table when set up. The leg and board structures and their connection to each other is in all respects similar to those previously described and similar parts are designated by the same reference characters. In the form shown in Figs. 40 8 to 11 the locking strut 35-36 which acts directly on upper cross brace 21 is replaced by a shorter strut comprising two members 50 and 51 acting indirectly on the upper cross brace 21 through a wedging engagement with strut 25. Members 50 and 51 are respectively pivoted as at 52 to leg members 26 and 27, and are connected together at their ends remote from said pivots by a cross piece 53 preferably formed of 45 metal. The cross piece 53 is shown as secured to members 50 and 51 (see Fig. 11) by crossed brace rods 54, the end portions of which extend through the parts and are bent over or upset in the same fashion as described with regard to 50 diagonal brace rods 23.

The length of members 50-51 and the position of cross piece 53 thereon is made such that when the table is set up as shown in Fig. 8, cross piece 53 is wedged tightly against strut 25 in turn wedging the latter tightly into slot 60 22 of upper cross brace 21 thus holding the table rigidly in set up position until strut member 50-51 is forcibly moved upwardly. When the table is set up strut 50-51 is slightly past dead center.

To maintain the lower end of strut members 65 50-51 in proper relation with strut 25 when the table is in folded condition and while it is being folded or set up, cross piece 53 is constrained to slide in a guideway 55 formed by a rod 56, the 70 ends of which are bent and secured on the strut 25 to space the rod a sufficient distance to permit the cross piece 53 to slide beneath it. Preferably the upper edge of cross piece 53 is provided with a recess 57 in which rod 56 engages. In the form 75 shown in Figs. 8 to 10 the sliding linkage 44-42

has been replaced by a chain 58 of suitable length but it will be understood that these structures are merely illustrative of any suitable type of collapsible connection between the parts at this point. 5

While I have shown what is in effect a three leg table it will be obvious that the same principle of construction is applicable to a four leg table or the character of the leg units can be reversed, that is, the triangular frame structure could provide a two point support and legs 17-18 be brought together to form a single support or could take the form of a single member. 10

I claim:

1. An ironing table comprising an ironing board, a pair of leg members pivoted to the under side of the board and pivoted together at their lower ends to form, with the board, a triangular support when the table is in set-up position, the pivotal connection of one of said leg members to the board being fixed, and a guide for the pivotal connection of the second leg member permitting limited sliding motion thereof toward and from the fixed pivot of the first leg member to permit folding of the leg members against the under side of the board, a third leg member pivoted to the under side of the board between the pivots of said pair of leg members and forming with one of said leg members a crossed support, the pivotal connection of said third leg member being 30 fixed, a strut member releasably engageable between that leg member having a slideable pivot and said crossed support to releasably hold said slideable pivot in its position remote from the fixed pivots of the other leg members to lock 35 the table in set-up position, and a connection between those leg members having fixed pivots to prevent their separation beyond a predetermined limit. 40

2. An ironing table comprising an ironing board, a pair of legs pivoted to the underside of the board, cross braces connecting said legs so that they swing as a unit, a frame structure forming a third supporting leg, said frame structure comprising leg members pivoted to the 45 underside of the board on opposite sides of the pivot of said pair of legs, longitudinally of the board, the leg members of the frame being pivotally connected together to form, with the board, a triangular support when the table is in set up 50 position, the pivotal connection of one of said leg frame members with the board being fixed, and a guide for the pivotal connection of the second leg frame member permitting limited sliding motion thereof toward and from the fixed 55 pivot of the other leg frame member to permit folding of said frame structure against the underside of the board, a locking strut member pivoted to that leg member of said frame which is provided with the slideable pivot and engageable with one of said cross braces to releasably hold said frame in set up triangular relation and a connection between the pair of legs and a leg member of said frame to prevent their separation beyond a predetermined limit. 60

3. An ironing table comprising an ironing board, a pair of legs pivoted to the underside of the board, cross braces connecting said legs so that they swing as a unit, a frame structure forming a third supporting leg, said frame structure comprising leg members pivoted to the underside of the board on opposite sides of the pivot of said pair of legs, longitudinally of the board, the leg members of the frame being pivotally connected together to form, with the 70 75

board, a triangular support when the table is in set up position, the pivotal connection of one of said leg frame members with the board being fixed, and a guide for the pivotal connection of the second leg frame member permitting limited sliding motion thereof toward and from the fixed pivot of the other leg frame member to permit folding of said frame structure against the underside of the board, a locking strut member pivoted to that leg member of said frame which is provided with a slideable pivot and engageable with one of said cross braces to releasably hold said frame in set up triangular relation and a linkage between the pair of legs and a leg member of said frame to prevent their separation beyond a predetermined limit, said strut being extended beyond its pivot sufficiently to engage the underside of the board upon collapse of the frame to maintain said strut out of engagement of said cross brace as the parts move to folded position.

4. An ironing table comprising an ironing board, a pair of legs pivoted to the underside of the board, cross braces connecting said legs so that they swing as a unit, a frame structure forming a third supporting leg, said frame structure comprising leg members pivoted to the underside of the board on opposite sides of the pivot of said pair of legs, longitudinally of the board, the leg members of the frame being pivotally connected together to form, with the board, a triangular support when the table is in set up position, the pivotal connection of one of said leg frame members with the board being fixed, and a guide for the pivotal connection of the second leg frame member permitting limited sliding motion thereof toward and from the fixed pivot of the other leg frame member to permit

folding of said frame structure against the underside of the board, a locking strut member connecting that leg member of said frame which is provided with a slideable pivot and the member of the frame having a fixed pivot, said locking strut member being pivoted to one of said frame members and having a sliding connection with the other member, and a connection between the pair of legs and a leg member of said frame to prevent their separation beyond a predetermined limit. 5

5. An ironing table comprising an ironing board, a pair of legs pivoted to the underside of the board, cross braces connecting said legs so that they swing as a unit, a frame structure forming a third supporting leg, said frame structure comprising leg members pivoted to the underside of the board on opposite sides of the pivot of said pair of legs, longitudinally of the board, the leg members of the frame being pivotally connected together to form, with the board, a triangular support when the table is in set up position, the pivotal connection of one of said leg frame members with the board being fixed, and a guide for the pivotal connection of the second leg frame member permitting limited sliding motion thereof toward and from the fixed pivot of the other leg frame member to permit folding of said frame structure against the underside of the board, a locking strut member pivoted to that leg member of said frame which is provided with the slideable pivot and having its opposite end slidably connected to that frame member which has a fixed pivot, and a connection between the pair of legs and a leg member of said frame to prevent their separation beyond a predetermined limit. 10 15 20 25 30 35

GEORGE W. LEWIS.
